UNITED STATES PATENT OFFICE.

JOHN A. BRILL, OF PHILADELPHIA, PENNSYLVANIA.

DESIGN FOR A SIDE FRAME FOR CAR-TRUCKS.

SPECIFICATION forming part of Design No. 26,405, dated December 15, 1896.

Application filed November 8, 1896. Serial No. 610,987. Term of patent 14 years.

To all whom it may concern:

Be it known that I, JOHN A. BRILL, a citizen of the United States, and a resident of Philadelphia, in the county of Philadelphia and State of Pennsylvania, have invented and produced a new and original Design for Side Frames for Car-Trucks, of which the following is a specification.

My invention relates to a new and original design for a side frame for a car-truck; and it consists in the shape or configuration of the same, substantially as hereinafter described, and shown in the accompanying drawings, forming part of this specification, in which—

Figure 1 is a plan view; Fig. 2, a side elevation; Fig. 3, an end elevation; and Fig. 4, a sectional elevation on the line $x x$, Fig. 2.

The side frame is substantially rectangular and comprises the following elements, having the disposition or configuration substantially as herein shown and described.

At 1 are inverted-U-shaped yokes, joined together adjacent the top and bottom by parallel bars 2 3, and extending between the bars 2 3 perpendicularly are ribs 4, equidistant from the yokes, the ribs 4 extending outwardly from the inner side of the frame to form parallel projecting walls 5 and 6, and from the tops and bottom of the walls, extending in opposite directions and merging into the upper bar 2, are curved webs 7 8, and between the inner lower portions of the walls extend the curved web 9, thus forming a

rectangular open top receiving-pocket on the 35 inner side of the frame. A rib 10, centrally disposed, extends along the top bar 2 and outer legs 11 of the yokes 1, both the inner legs 11 12 of the yokes being recessed, as at 13, at their lower extremities. 40

The top bar 2, including the rib 10, has a configuration in cross-section, as shown at 14, Fig. 2, and the lower bar 3 has a configuration in cross-section, as shown at 15, Fig. 2.

Extending between the angle made by the 45 intersection of the top bar 2 and ribs 4 and that made by the lower bar 3 and the inner legs 12 of the yokes 1 are oppositely-inclined bars or chords 16, of a configuration in cross-section, as indicated at 17, Fig. 2, and between the angle formed by the intersection of the top bar 2, lower bar 3, and ribs 4 extends 50 an X-shaped chord 18.

At the top of the yokes 1 and depending down on each side thereof are oval-shaped 55 caps 19, having a circular recess, as indicated at 20, dotted lines, Fig. 1.

Having described my invention, I claim—

The design for a side frame for car-trucks, substantially as herein shown and described. 60

Signed at New York, in the county of New York, and State of New York, this 17th day of October, A. D. 1896.

JOHN A. BRILL.
